BABY BOTTLE NIPPLE PUNCH

Polly Nixon Slick, San Antonio, Tex., assignor to Institute of Inventive Research, San Antonio,
Tex., a foundation of the State of Texas

Application October 29, 1949, Serial No. 5,775

Term of patent 14 years

(Cl. D83—1)

To all whom it may concern:

Be it known that I, Polly Nixon Slick, a citizen of the United States, residing at San Antonio, in the county of Bexar and State of Texas, have invented a new, original, and ornamental Design for a Baby Bottle Nipple Punch, of which the following is a specification, reference being had to the accompanying drawings, forming a part thereof, wherein:

Figure 1 is a perspective view showing the front and side of a baby bottle nipple punch embodying my new design;

5—5 in Figure 3 and looking in the direction of the arrows to show the openings in the upright member. The large lower base member in Figure 3 is omitted from Figure 5.

I claim:

The ornamental design for a baby bottle nipple punch, substantially as shown.

POLLY NIXON SLICK.
